UNITED STATES PATENT OFFICE.

CHARLES STEIN, OF CHICAGO, ILLINOIS.

SADDLE-YOKE STRUCTURE.

1,281,868.

Specification of Letters Patent. Patented Oct. 15, 1918.

Application filed September 29, 1916. Serial No. 122,803.

To all whom it may concern:

Be it known that I, CHARLES STEIN, a citizen of the United States, and a resident of Chicago, in the county of Cook and State of Illinois, have invented certain new and useful Improvements in Saddle-Yoke Structures, of which the following is a specification.

My invention relates to saddle yoke structures for supporting loads on the backs of a team of draft animals.

My invention is of particular utility with two-wheeled vehicles or carts such as ammunition carts or field kitchen carts. Such carts must follow the soldiers over all conditions of ground and must take bumps and ditches or any other irregularities as they may come and sometimes at considerable speed. In these carts the center of gravity of the weight is in front of the axle and considerable weight must therefore be supported by the team of animals drawing the cart.

The object of my invention is to provide an improved saddle yoke structure by means of which the load on the vehicle pole is supported on the backs of the animals, and so constructed and arranged that it will yield and follow all the sudden relative movements of the animals during travel.

A structure embodying the features of my invention is illustrated on the accompanying drawings in which—

Figure 1 is a side elevational view of a cart and one of the horses showing the application of my improved saddle yoke structure.

Fig. 2 is a front elevational view of the saddle yoke structure,

Fig. 3 is a plan view of the structure,

Fig. 4 is a sectional view on plane 4—4, Fig. 3, and

Fig. 5 is an enlarged sectional view on plane 5—5, Fig. 4.

Describing the structure, a frame body 10 which may be of wood has the metallic top plate 11 secured thereto as by bolts 12. Passing through the center of the frame is the eye-bolt 13 for supporting the chain 14.

At the sides of the center the top plate has the longitudinal slots 15 and 16 through which extend guide bolts 17 and 18 at the inner ends, respectively, of the yoke arms 19 and 20, these arms being slidable longitudinally on the plates and held thereto by the bolts, the frame body 10 having the slots 21

and 22 for accommodating the heads of the bolts. At the ends of the top plate are the bridge pieces 23 and 24 which span over the arms 19 and 20, respectively, and guide them during their longitudinal movement. These bridge pieces are wider than the arms 19 and 20 so that the arms may also swing horizontally. The top plate may have the side ridges 25 and 26 for inclosing and protecting the arms.

The arms 19 and 20 are preferably of spring material and are pivoted at their outer ends to saddle structures S. As shown, each saddle structure comprises a supporting casting and back engaging pads. The casting comprises the two plate sections 27 and 28 connected by the yoke 29 from which parallel ears 30 extend upwardly. Extending between these ears is a pin 31 pivotally receiving the end of the corresponding arm of the yoke structure. The saddle plate sections 27 and 28 support pad structures 32 for engaging the back of the animal.

In Figs. 1 and 2 the operation of the device is shown. The saddle structures S are placed on the backs of the horses or other animals of the team and are secured by ordinary cinch straps 33 engaging around the animals' bodies. The chain 14 is then looped around the pole p of the cart C so that the weight on the pole is supported from the backs of the animals. The application of my improved yoke structure does not interfere with the ordinary harness h. The animals will still steer the vehicle through the chains 34 connecting the pole end and the collars, but the weight on the pole will be supported from the backs. As shown, a fitting 35 is secured to the pole and has a series of holes or loops 36 through which the chain can be looped to adjust its connection with the pole.

I thus produce a saddle yoke structure which is strong yet very flexible and automatically adjustable to adapt itself to and to follow the sudden relative movements of the animals during travel of the vehicle over broken and uneven ground.

I do not, of course, desire to be limited to the exact construction and arrangement shown and described as modifications are no doubt possible which would still come within the scope of the invention.

I claim as follows:

1. A saddle yoke structure for draft ani-

- 5 mals comprising a frame, arms extending from said frame and pivoted at their inner ends thereto for lateral swing, and saddle structures secured to the outer ends of said 5 arms.
2. A saddle yoke structure for draft animals comprising a frame, and arms extending from said frame and pivoted at their inner ends thereto for lateral swing, said 10 arms being free to shift longitudinally on said frame.
3. A saddle yoke structure for draft animals comprising a frame, and arms extending from the ends of said frame, a pivot connection securing the inner ends of said arms to said frame but permitting longitudinal shift of said arms on said frame.
4. A saddle yoke structure for draft animals comprising a frame, arms extending from the ends of said frame, a pivot connection securing the inner ends of said arms to said frame but permitting longitudinal shift of said arms on said frame, and means for permitting limited lateral swing of said 25 arms.
5. A saddle yoke structure for draft animals comprising a frame having longitudinally extending slots, and arms extending from the ends of said frame and having pin connection at their inner ends in said slots longitudinally shiftable with reference to said frame, said arms being free to swing laterally in any position of longitudinal adjustment, and means for limiting such lateral swing.
6. A saddle yoke structure for draft animals comprising a frame, side arms for said frame, and a pivot connection between the inner ends of said arms and said frame for permitting lateral swing of said arms, said pivot connections being shiftable longitudinally along said frame.
7. A saddle yoke structure for draft animals comprising a frame, side arms for said frame, and a pivot connection between the inner ends of said arms and said frame for permitting lateral swing of said arms, said pivot connections being shiftable longitudinally along said frame.
8. A saddle yoke structure for draft animals comprising a frame, arms extending from said frame and having pin and slot connection at their inner ends with said frame, the pin being longitudinally shiftable in the slot, and saddle structures supported from the outer ends of said arms.
9. A saddle yoke structure for draft animals comprising a frame, arms having pin and slot connection at their inner ends with said frame to swing laterally and shiftable longitudinally on said frame, means for limiting the lateral swing, and saddle structures secured to the outer ends of said arms.
- In witness whereof I hereunto subscribe my name this 27th day of September, A. D., 1916.

CHARLES STEIN.
